UNITED STATES PATENT OFFICE.

GEORGE A. MARTIN, OF MYERSTOWN, PENNSYLVANIA.

STOP-MOTION.

SPECIFICATION forming part of Letters Patent No. 732,573, dated June 30, 1903.

Application filed February 19, 1902. Serial No. 94,811. (No model.)

To all whom it may concern:

Be it known that I, GEORGE A. MARTIN, a citizen of the United States, and a resident of Myerstown, in the county of Lebanon and State 5 of Pennsylvania, have invented a new and Improved Stop-Motion, of which the following is a full, clear, and exact description.

The object of the invention is to provide a new and improved stop-motion, more especially designed for use on knitting-machines, which is simple and durable in construction and arranged to insure a quick stopping of the machine as soon as a yarn or thread breaks or gets caught in the knot-catchers or becomes fastened on the spool or runs slack from the spool.

The invention consists of novel features and parts and combinations of the same, as will be more fully described hereinafter and 20 then pointed out in the claims.

A practical embodiment of the invention is represented in the accompanying drawings, forming a part of this specification, in which similar characters of reference indicate corresponding parts in all the views.

Figure 1 is a side elevation of the improvement as applied to a circular-knitting machine. Fig. 2 is an enlarged plan view of the improvement. Fig. 3 is a sectional plan 30 view of part of the same on the line 33 of Fig. 5. Fig. 4 is a plan view of the knot-catchers. Fig. 5 is a front elevation of the improvement. Fig. 6 is a similar view of the same, showing the parts on one side in position 35 when the thread or yarn is broken; and Fig. 7 is a sectional side elevation of part of the improvement, the section being on the line 77 of Fig. 3.

On the bed of the knitting-machine is secured a horizontally-extending bracket A, supporting a hollow post B, through which extends a drop-rod C, provided near its upper end with a collar C', (see Fig. 7,) adapted to be engaged at the under side by a lever 40 D, fulcrumed on a head B', secured to the upper end of the post B, the said lever D being pressed on at one end by a spring E to swing the lever from under the collar C' as soon as the lever is released by a catch F, 45 fulcrumed on the head B'. Now when this catch F is swung out of engagement with the front end of the lever D then the spring E

swings the lever D out of engagement with the collar C', so that the rod C drops in the hollow post B and in doing so actuates the 55 belt-shifting device to move the belt from the fast pulley to the loose pulley and stop the machine.

As shown in Fig. 1, the lower end of the drop-rod C is provided with a foot C², adapted 60 to engage a disk G, adjustably secured by a set-screw or other means on an arm G', projecting from a shaft G², carrying a belt-shifter arm G³, connected with a belt-shifter H. The disk G is made adjustable, so that the device 65 can be readily adapted to knitting-machines of different makes and sizes. Now when the rod C drops, as above described, its foot C² drops onto the disk G, so as to impart a downward-swinging motion to the arm G', 70 to turn the shaft G² and swing the arm G³ outward to move the belt-shifter H and shift the belt from the fast pulley to the loose pulley. Normally the rod C and its foot C² are suspended a distance above the disk G, as indicated in Fig. 1.

Now in order to swing the catch F out of engagement with the lever D whenever a thread or yarn breaks or when the yarn is caught or runs too slack I provide the following device: The catch F is provided with a pin F', normally engaged at the under side by the inner ends of two levers I, fulcrumed at I' on the head B' and extending in opposite directions, each of the levers I having its 85 outer end I² curved and engaged by an eye J, held to swivel in an arm K' of a bell-crank lever K, normally held in a horizontal position by the yarn or thread L, passing through oppositely-disposed notches N' in a weighted 90 lever-frame N, between the side arms of which passes the bell-crank lever K. The lever-frame N is formed with a shaft N², journaled in the outer end of the head B', and on the said shaft N² is secured a rearwardly-extending arm N³, carrying a counterweight N⁴, so as to normally hold the lever-frame N in a horizontal position, as plainly indicated in Fig. 5.

Now in case the thread or yarn L breaks 100 then the bell-crank lever K swings downward by its own weight and in doing so causes its arm K' and eye J to impart a downward-swinging motion to the lever I, so that the

inner end thereof presses the pin F' in an upward direction to swing the catch F upwardly and out of engagement with the front end of the lever D, so that the spring E thereof swings the front end of the lever outward and out of engagement with the collar C' to allow the rod C to drop for shifting the belt, as previously explained.

In case the yarn becomes fast between the machine and its spool then the pull exerted on the yarn by the machine causes a swinging of the lever-frame N in a downward direction, and as the bell-crank lever K rests on the downwardly-moving yarn L it is evident that it swings with the frame, and its arm K' and eye J impart a swinging motion to the lever I to swing the catch F out of engagement with the lever D.

A similar movement takes place when a knot gets caught in a knot-catcher, and in case the yarn becomes too slack between the spool and the machine then the weight of the bell-crank lever K on the yarn overcomes the tension thereof, and consequently swings downward to impart a swinging motion to the lever I for swinging the catch F upward.

In order to insure a quick dropping of the rod C, I provide a spring-pressed arm O, pressing on the upper end of the rod C, the said arm O being secured on a shaft O', journaled in the head B' and having an arm O² connected by a link O³ with the rear end of the lever D. (See Figs. 2 and 3.) Now when the lever D is released and the spring E swings it into an outermost position then the lever exerts a pull on the link O³ and arm O² to swing the arm O downward, and thereby cause the latter to exert a downward pressure on the rod C to insure a positive downward movement of the rod for swinging the arm G' downward.

Each of the yarns L unwinds from the usual spool P, the yarn extending upward from the spool and passing through an eye Q and then through a slotted knot-catcher R and then passes to the notches N' of the lever-frame N, as previously explained, it being understood that the yarn passes from the notches N' to the machine in the usual manner.

The eyes Q and knot-catchers R are secured on the bracket A, as plainly shown in Figs. 1 and 4.

Having thus described my invention, I claim as new and desire to secure by Letters Patent—

1. A stop-motion, comprising a lever connected with the belt-shifter of the machine on which the stop-motion is applied, a hollow post supported on the machine, a drop-rod extending through said post and adapted to impart a swinging motion to the lever, a supporting device for the drop-rod, a releasing device, a counterbalanced device over which the yarn passes, a device resting on the yarn and controlling the releasing device, and a device engaging the drop-rod and arranged

to impart a downward movement thereto, the said device being connected with the supporting device and actuated thereby when the supporting device is released, as set forth. 70

2. A stop-motion comprising a lever having a member connected with a belt-shifter, and a member provided with an adjustable device on its free end, a drop-rod adapted to engage said adjustable device to impart a swinging motion to said lever, a supporting device for the said drop-rod, to hold the latter normally out of engagement with the adjustable device on the lever, the said supporting device comprising a spring-pressed lever, engaging a collar on the said drop-rod, to hold the latter normally suspended, a locking-catch for holding the latter in a closed position, and a releasing device for the said catch, controlled by the yarn, as set forth. 80

3. A stop-motion comprising a belt-shifting device a drop-rod for imparting a swinging motion to the belt-shifting device, a supporting device for the said drop-rod, to hold the latter normally out of engagement with the belt-shifting device, the said supporting device comprising a spring-pressed lever, engaging a collar on the said drop-rod, to hold the latter normally suspended, a locking-95 catch for holding the latter in a closed position, a releasing device for the said catch, controlled by the yarn, the said releasing device consisting of a lever engaging at one end a pin on the said catch, and a bell-crank lever having an eye engaging the other end of the said lever, the said bell-crank lever resting on a yarn on its passage from the spool to the machine, as set forth. 100

4. A stop-motion comprising a drop-rod for imparting a swinging motion to the belt-shifting device, a supporting device for the said drop-rod, to hold the latter normally out of engagement with the belt-shifting device, the said supporting device comprising a spring-pressed lever, engaging a collar on the said drop-rod, to hold the latter normally suspended, a locking-catch for holding the latter in a closed position, a releasing device for the said catch, controlled by the yarn, the 115 said releasing device consisting of a lever engaging at one end a pin on the said catch, a bell-crank lever having an eye engaging the other end of the said lever, the said bell-crank lever resting on a yarn on its passage 120 from the spool to the machine, and a counterbalanced, notched lever-frame, over which passes the yarn, as set forth.

5. A stop-motion provided with a counterbalanced lever-frame, having notches for the 125 passage of the yarn, and a bell-crank lever fulcrumed on a shaft of the said lever-frame and resting on that part of the yarn extending between the notches of the lever-frame, the said bell-crank lever controlling the releasing device, as set forth.

6. A stop-motion comprising a drop-rod for actuating the belt-shifter, a spring-pressed lever for supporting the said drop-rod in a nor-

- mal uppermost position, a catch for locking the lever in position when engaging the said drop-rod, and a releasing device for the said catch, to swing the latter out of engagement 5 with the lever, the said releasing device being controlled by a bell-crank lever resting with one arm on the yarn, and by a lever-frame having notches through which passes the yarn, as set forth.
- 10 7. A stop-motion, comprising a lever forming part of a belt-shifting device, a drop-rod for actuating said lever, a spring-pressed lever engaging a collar on the drop-rod to hold the rod normally suspended above the said 15 lever, a catch for locking the spring-pressed lever in position when engaging the said drop-rod, a releasing device for the catch comprising a releasing-lever engaging said catch, a bell-crank lever for actuating the releasing- 20 lever, the said bell-crank lever resting on the yarn, and means actuated by the said spring-pressed lever when released for imparting a positive downward motion to the drop-rod, as set forth.
- 25 8. A stop-motion, comprising a lever connected with the belt-shifter of the machine on which the stop-motion is applied, a disk adjustably secured on the free end of said lever, a horizontally-extending bracket on the 30 said machine, a hollow post supported on said bracket, a drop-rod extending through said

post and adapted to engage the said disk on the lever to impart a swinging motion to the lever, a supporting device for the said drop-rod to hold the latter suspended above the lever, the said supporting device comprising a spring-pressed lever, a locking-catch for the lever, and a releasing device for the catch controlled by the yarn, and an arm engaging the drop-rod, and connected with the spring- 35 pressed lever, the said arm being actuated by the lever when the latter is released, as set forth.

9. A stop-motion, comprising a drop-rod for actuating the belt-shifter, a spring-pressed lever for supporting the drop-rod in a normal uppermost position, means for locking the lever in supporting position against the tension of its spring, a releasing device for said means, an arm engaging the upper end of the drop-rod, a shaft mounted to turn and carrying said arm, and a link connecting the said spring-pressed lever with an arm on said shaft, as set forth.

In testimony whereof I have signed my 55 name to this specification in the presence of two subscribing witnesses.
